[57] CLAIM

The ornamental design for a ring, as shown and described.

DESCRIPTION

FIG. 1 is a perspective view of a ring, showing my new design shown in a position of use as a finger ring; FIG. 2 is a front elevational view, the rear elevational view being a mirror image thereof;

FIG. 3 is a left side elevational view, the right side elevational view being a mirror image thereof; FIG. 4 is a top plan view thereof; and,

FIG. 5 is a bottom plan thereof.
The broken line showing of the position of use in FIGS. 1—5 is for illustrative purposes only and forms no part of the claimed design.
